UNITED STATES PATENT OFFICE.

JOHN DOGGETT, OF PLAIN CITY, OHIO.

TELEGRAPH-KEY.

SPECIFICATION forming part of Letters Patent No. 445,442, dated January 27, 1891.

Application filed July 28, 1890. Serial No. 360,219. (No model.)

To all whom it may concern:

Be it known that I, JOHN DOGGETT, a citizen of the United States, residing at Plain City, in the county of Madison and State of 5 Ohio, have invented a new and useful Telegraph-Key, of which the following is a specification.

This invention has relation to improvements in telegraph-keys, and is especially intended 10 as an improvement upon United States Patent No. 384,350, granted me June 12, 1888, for combined telegraph key and sounder.

The objects of the present invention are to provide for a simple and convenient means 15 for converting the key from a mechanically-operated to an electrically-operated key and sounder, and when mechanically operated to provide means for adapting either end of the key-lever for operation as an ordinary telegraph-key; to provide means for preventing a loud sound by the set-screw of the long arm 20 of the key coming in contact with the base when the short or long end of key-lever is used; to provide additional insulated posts for 25 relay and main-line attachments and means for cutting off the sounder from relay and main line, whereby the key and sounder will work mechanically or with the use of local battery and without interfering with the main line; to provide the shortest arm of key-lever with means for assisting in the adjustment of the stroke of the same when used 30 mechanically; to provide a means for adjusting the tension of the spring between the sounder and long arm of key-lever; to improve the means for securing the bearing-ears of the key-lever to the base; to provide 35 means for cutting off the relay and main-line attachments for main-line business and local circuit for learners; to provide means for 40 raising the short end of key-lever when the instrument is operated by electricity, made necessary by the fact that when so operated said key-lever is disconnected or detached 45 from the connecting-rods, and therefore has no spring, and, furthermore, in other details of construction hereinafter appearing.

With the above objects in view the invention consists in certain features of construction hereinafter specified, and particularly pointed out in the claims.

Referring to the drawings, Figure 1 is a perspective of an instrument constructed in accordance with my invention. Fig. 2 is a plan. Fig. 3 is a longitudinal vertical section, portions being shown in side elevation. Fig. 4 is a transverse vertical section. Fig. 5 is a detail in bottom plan of a portion of the key-lever and the switch. Fig. 6 is a diagrammatic view of the instrument, illustrating 60 the circuits, battery, and relay.

Like numerals of reference indicate like parts in all the drawings.

1 designates the base, which at its center has secured thereupon a standard 2, rising 65 vertically from the base and extending parallel to the base and from the standard to form a bar 3. The bar 3 is provided with a longitudinal slot which forms upon the upper side of said bar a resonant arm 4, and 70 said bar is reduced at its forward end and has threaded upwardly through the same a percussion set-screw 5. The rear end of the bar projects a slight distance beyond the opposite end of the standard, is reduced and 75 has mounted thereon a supplemental superimposed standard 6, the base of which is provided with a threaded shank 7, passing through the bar and clamped in position by means of a set-nut 8. The upper portion of 80 the bar overhangs and extends parallel with the resonant arm 4 and is provided with percussion set-screws 9 and 10, located at different points along the supplemental standard and depending from the same. Near its 85 outer end the bar 3 is transversely recessed, as at 11, upon its upper side, and seated in the same is a U-shaped transversely-disposed bearing-yoke 12, secured to the bar by means of a screw 13 passing through the yoke and 90 into the bar. The terminals of the yoke are provided with percussion bearing-screws 14, inwardly disposed, and receive the conical trunnions 15 of the sounding-arm 16, to the upper side of which is secured the armature 95 17, adapted to have intermittent contact with the helices 18. Under the supplemental standard the arm 16 is provided with a percussion-screw 19. By adjusting either the screws 9 or 10 so as to have contact with the 100 sounding-arm the pitch of said sounding-arm will be altered, as will be apparent. The

standard 2 is provided with a recess or opening 20, and in rear of the standard there is secured upon the base a transverse rib 21, between which and the standard is located a 5 key-lever-bearing yoke 22, secured in position by means of a couple of screws 23 passed upwardly through the base and into the yoke. 24 designates the key-lever, which at one side of its center is provided with laterally-disposed conical trunnions 25, having adjustable bearings in percussion-screws 26 passed through the terminals of the yoke 22. By locating the trunnions 25 at one side of the center of the key-lever a short arm 26 and a long arm 15 27 are formed, each of said arms extending out a suitable distance over the base and provided with the usual buttons 28. The shorter arm 26 is provided with a percussion-screw 29, terminating in a contact-point 30, adapted for 20 contact with a contact-point 31, secured to the base under the arm, and interposed between the base and the under edge of the arm is a coiled spring 32, having a tendency to elevate the arm, said spring being removable. 25 Recesses 33 are formed at each side of the fulcrum and in the under edge of the sounding-arm 16, and through the same are passed bearing-pins 34. Mounted pivotally upon the inner bearing-pin 34 is the upper end of a 30 pending connecting-rod 35, the lower end of which passes loosely through and depends below a vertical opening 36, formed in the longest arm 27 of the key-lever, and flush with the bottom edge of said arm is provided with 35 a transverse kerf or recess 37, said rod passing through a suitable opening formed in the bar 3 and adapted for reciprocation in said opening. Pivotedly connected at its upper end to the outer bearing-pin 34 is a second 40 rod 38, located at the opposite side of the fulcrum 15 of the sounding-arm, at which the rod 35 is located, and said rod 38, after depending through a suitable vertical opening formed in the bar 3, extends down through an 45 opening 39, formed in the longest arm 27 of the key-lever, and flush with the lower edge of the same when the lever is raised is provided with a transverse kerf or recess 40. Above the key-lever the rod 39 is threaded, 50 and mounted thereon is a set-nut 41, between which and the under side of the bar 3 is located a light coiled spring 42, the tensile power of which may be increased or diminished by an adjustment of the set-nut 41, 55 which, like all other nuts employed herein, is suitably milled.

Pivoted, as at 43, to the under side of the longer arm 27 of the key-lever, and between the lower ends of the two rods 35 and 38, is a 60 switch-lever 44, having at its outer end a button 45 or knob, and at its inner end and opposite sides thereof provided with wedge-shaped flanges or shoulders 46. By swinging the switch-lever to a central position, or at a 65 right angle to the arm 27, the flanges 46 will be free from the kerfs 37 and 40 of the rods 35 and 38, respectively, so that the key will

be adapted for use in connection with the main-line circuit or for electrical use. By throwing the switch-lever so that one of the flanges 46 will take into the kerf 40 of the rod 41 the shorter arm 26 of the key-lever will be adapted to work mechanically and the opposite arm not adapted for work. Now by throwing the lever in the opposite direction, 75 so that the kerf 37 is engaged, the longest arm 27 is adapted to work mechanically and the shortest arm 26 not to work.

Near the outer end of the arm 27 there is located a percussion-screw 47, the lower end 80 of which depends through the arm and has contact with a rubber buffer 48, secured to the base under the arm. By means of this buffer and screw 47 the loud sound caused by the set-screw coming in contact with the 85 base when the short or long arms of the key-lever are operated is avoided.

In Fig. 6 I have illustrated my key in connection with my improved relay designed for use in connection therewith. The key and sounder may be used independently, and when so used the short lever 61 is in the position having contact with the post 59, the main circuit coming in by the wire 56, through the relay-coils by wire 65* to the lever 61, 90 and to contact-point under key through wire 70, from which it passes through wire 66 to the binding-post 58 and by wire 57 to main line. The local circuit, however, will be from the local battery by the wire 55 to the relay binding-post 52, from thence by the removable wire 72 to the binding-post 53, by wire 64 to binding-post 65 of key-base, through metal key-base to contact-points of key, (when closed,) by wire 69 to sounder-coils 18, 105 thence by wire 67 to post 63, and by wire 62 back to battery, so that the key will operate the sounder. When it is desired to operate the main line by the key, the lever 61 is swung into contact with the post 60, when 110 the current will enter by the wire 56, pass through the relay-coils, attracting the relay-armature, closing its contact-points to close the local circuit, leaving the relay by the wire 65*, passing through the lever 61 into key-base by the stud 60, and when key is closed 115 will return to main line by the wires 66 and 57. The lever 61 and removable short wire 72 are merely used to interfere, so as to prevent the local battery from carrying the main-line current from the relay to the sounder. The main-line current being the stronger, the conduction can only be accomplished through the power of the local battery. The contact-point under the key-lever is insulated for 120 main-line use and also for local use. This permits one cut-out lever to answer the purpose of two, the portable or removable wire 72 serving the purpose of a second lever, said portable wire 72 being entirely removed from 125 relay when the line is used with the sounder and key and put on or attached to the two local posts of the relay when a cut-out is required. It is evident that by operating the

switch-lever 61 the sounder may be disconnected from the main line and used mechanically or simply connected with the local circuit, and yet not interfere with the business 5 of the main line.

From the above construction it will be apparent that I accomplish the objects of the invention in a cheap, simple, and efficient manner, and that I have succeeded in producing an exceedingly complete, compact, and convenient instrument capable of all the changes herein mentioned, adapting it for regular business or to be used electrically or mechanically for the purpose of teaching beginnners, the conversion of the instrument being accomplished by convenient means and always ready at hand for instant use.

Having described my invention, what I claim is—

1. In a telegraph-key, the combination, with a sounding-arm, a support for the same, and a pivoted key-lever having arms extending at each side of its fulcrum, of pivoted rods depending from each side of the pivot of the sounding-arm and terminating below one of the arms of the key-lever and a pivoted switch located between said arms and adapted to engage and rigidly connect either one of said rods with the key-lever, substantially as specified.

2. In a telegraph-key, the combination, with a pivoted sounding-arm, a support for the same, and a pivoted key-lever extended at each side of its pivot to form operating-arms and provided in one of said arms with a pair of openings, of a pair of pivoted rods, one located at each side of the pivot of and depending from the sounding-arm and each passing through an opening in the key-lever, 40 and a switch-lever pivoted to the under side of the key-lever between the lower ends of the rods and provided at each side of its pivoted end with a shouldered flange adapted to engage kerfs formed in the lower ends of the 45 rods, and thereby lock either of said rods rigidly with said key-lever, substantially as specified.

3. In a telegraph-key, the combination, with a pivoted sounding-arm, a support for the

same, and a pivoted key-lever arranged under 50 the arm, of a pair of rods pivoted at their upper ends to and at each side of the fulcrum of the sounding-arm and having their lower ends depending through openings formed in the key-lever, one of said rods being threaded, 55 a set-nut threaded on the rod above the key-lever, and a coiled spring encircling the rod and interposed between the said nut and the support for the sounding-arm, and means for locking either of said arms rigid with the key-lever, substantially as specified.

4. The relay having the posts 52 and 53, in combination with the battery 54, the wire 55, leading from the battery to the post 52, the key-connections between the same and 65 the key and post 53 and armature and between the key and relay-coils, and the portable wire 72, connecting the posts 52 and 53, substantially as specified.

5. A telegraph-key the base of which is provided with the binding-posts 58 63 65 and the lever 61 and the insulated and non-insulated posts 59 and 60, respectively, in combination with a relay and battery, said relay having the posts 50 to 53, inclusive, the wire 75 55, leading from the battery to the post 52 of the relay, the wire 62, leading from the battery to the post 63 of the key, the wire 64, leading from the post 53 to the post 65 and forming, in connection with the wires 55 and 80 62, a local circuit, the wire 56 of the main line connected to the post 50 of the relay, and the main-line wire 57, connected to the post 58 of the key and to the contact-point, the wire 67, leading from the post 63 to sounder-coils, the 85 wire 69, leading from coils to contact-point under key, the wire 70, leading from post 69 to contact-point under key, the wire 66, leading from contact-point of key to post 58, and the removable wire 72, connecting the posts 52 90 and 53, substantially as specified.

In testimony that I claim the foregoing as my own I have hereto affixed my signature in presence of two witnesses.

JOHN DOGGETT.
